UNITED STATES PATENT OFFICE.

HARRY A. SMITH, OF COLUMBUS, OHIO.

ATTACHMENT FOR PHONOGRAHS.

941,546.

Specification of Letters Patent. Patented Nov. 30, 1909.

Application filed July 10, 1908. Serial No. 442,906.

To all whom it may concern:

Be it known that I, HARRY A. SMITH, a citizen of the United States, residing at Columbus, State of Ohio, have invented new and useful Improvements in Attachments for Phonographs, of which the following is a specification.

This invention relates to phonographs, the object of the invention being to provide 10 mechanism whereby a plurality of records may be advanced to and moved away from the playing or reproducing position and successfully operated in connection with the reproducer, the mechanism being entirely 15 automatic and motion being imparted to the various elements of the mechanism from a single source of power which, in the preferred embodiment of the invention, consists of a spring motor contained within the 20 housing or casing of the apparatus and forming a part of the mechanism as a whole, the power generated by such motor being utilized to intermittently advance the records to and from the reproducing position, 25 and also to clutch and release the records successively and also to actuate the reproducer back and forth during its operative or outgoing movement and its return or inactive movement.

30 With the above and other objects in view, the nature of which will more fully appear as the description proceeds, the invention consists in the novel construction, combination and arrangement of parts as herein 35 fully described, illustrated and claimed.

In the accompanying drawings:—Figure 1 is a vertical longitudinal section taken through the casing of the machine, showing the record-moving mechanism in elevation, 40 the view being taken looking toward the ends of the cylindrical records. Fig. 2 is a vertical section taken at right angles to Fig. 1. Fig. 3 is a plan view of the record reproducing portion of the apparatus.

45 The machine comprises a box or casing A in which a portion of the mechanism is contained and upon which the remainder of the mechanism is mounted, said casing being shown as comprising a top 1 and bottom 50 2 and sides and ends 3.

Mounted in suitable hangers 4 connected to the under side of the top 1 are two sets of sprocket wheel shafts 5 and 6 each of which carries a pair of sprocket wheels 7 55 and 8 around which run parallel chains or record carriers 9, said chains being pro-

vided at opposite points and at suitable intervals with arcuate holders 10 upon which the cylindrical records 11 are mounted as shown in Figs. 1, 2 and 3. As shown in Fig. 1 the chains together with the records carried thereby travel in a rectangular path within a guard 12, the ends of which extend upward through openings in the top of the casing as shown, which casing is also provided with apertures in the top thereof through which the records 11 pass during the movement of the carrying chains.

The mechanism for actuating the chains and imparting intermittent movement thereto and to the records carried thereby comprises an initial spring operated arbor 13 to which is connected a suitable power spring 14 one end of which is connected to a part of the frame as shown at 15. The winding mechanism comprises pawl and ratchet members 16 and 17 respectively for holding the shaft after the spring is wound thereon, and said arbor is squared as shown at 18 to receive a suitable winding key like the key 80 of any ordinary clock mechanism. On the same arbor 13 there is mounted a spur gear wheel 19 which meshes with a pinion 20 on a counter-shaft 21 on which is another large spur gear wheel 22 which meshes with a 85 pinion 23 on another counter-shaft 24 having also fast thereon another spur gear wheel 25. The wheel 25 meshes with a spur gear wheel 26 fast on a cam shaft 27, all of said shafts being mounted in suitable bearings within the casing A.

Fast on the cam shaft 27 is a cam 28 having an abrupt radial shoulder 29 as shown in Fig. 1 while co-operating with said cam is one arm 30 of a cam lever, which arm 30 is 95 preferably provided with a roller 31 at the end thereof which operates against the peripheral face 32 of the cam 28. The other arm 33 of the cam lever has pivotally connected thereto a reciprocatory bar 34 to the 100 opposite end of which is connected a contractile spring 35 the opposite end of which is connected at 36 to a post 37 extending downward from the top 1 of the casing. The bar 34 carries a pawl 38 which engages 105 the teeth of a ratchet wheel 39 which is fast on a centrally arranged chain actuating shaft 40, said shaft being provided with oppositely arranged sprocket wheels 41 which engage at their upper sides with the sprocket 110 chains 9 hereinabove referred to. By means of the mechanism above described, it will

be observed that in each complete revolution of the wheel 26, an intermittent throw or movement is imparted to the shaft 40 and the sprocket wheels 41 and consequently 5 to the chains 9. In this way, the records are moved forward with a step-by-step motion, the records being carried successively to the point of reproduction and then successively moved onward beyond said point. The position or point of reproduction is shown best 10 in Fig. 1 in which 42 designates the reproducer beneath which one of the records is located while in the reproducing position.

The reproducer 42 is carried by a pivoted 15 arm 43 which is fulcrumed on a rod 44 supported by a frame 45 extending from the top 1 of the casing upward as shown in Fig. 1. The reproducing arm 43 is provided with a lever extension 46 which extends under a 20 feed screw 47 and over a return screw 48, the screws 47 and 48 being geared together by means of spur gear wheels 49 and 50 while the gear 49 meshes with and is driven by a similar gear wheel 51 which is in turn 25 driven by a pinion 52 on the shaft 53 of one of the friction cones hereinafter described by which the record is revolved. By reference to Fig. 3 it will be observed that the one feed screw 47 has comparatively fine 30 threads while the return screw 48 has comparatively coarse threads for effecting a comparatively quick return of the reproducer and it will also be observed that the lever 46 is provided with a nut segment 54 35 which engages the under side of the feed screw 47 and is also provided with another nut segment 55 which engages the upper side of the return screw 48. The lever 46 is so bent that one side only of the nut segments thereof may be thrown into engagement 40 with their respective screws at a time. When the reproducer 42 is moved downward to its operative position, the nut segment 54 is raised into threaded engagement with the 45 screw 47, and as the latter revolves the feed screw is fed lengthwise of the revolving record. When the reproducer 42 is elevated out of contact with the record, the nut segment 54 is moved downward out of operative 50 engagement with the feed screw 47 while the nut segment 55 is moved downward into the operative relation to the return screw 48, the latter operating to return the reproducer 42 quickly to its initial or 55 starting point.

Rotary motion is imparted to an individual record upon reaching the point of operation by means of a pair of oppositely arranged cones 56 and 57, 56 designating the 60 driving cone and 57 the tension cone. The cones 56 and 57 are in the nature of friction clutches being of a size adapting them to enter the opposite ends of the hollow cylindrical record as best illustrated in Figs. 2 65 and 3, the driving cone 56 being mounted on

the shaft 53 which is provided with a pulley 58 receiving a driving belt 59 from another pulley 60 mounted fast on a shaft 61 on which is also fast a spur a spur gear wheel 62 which is driven by the spur gear 70 wheel 19 above described thus providing for imparting rotary motion to the record.

The tension cone or clutch member 57 is pressed yieldingly toward the path of movement of the records by means of an expansion spring 63 which is coiled around the shaft or spindle 64 on which the cone 57 is mounted, said spring being interposed between the hub 65 of the cone and the bearing 66 in which the outer end of said spindle 64 is journaled. The outer periphery of the cone 57 is grooved to receive a band 68 which fits loosely therein and is engaged by the arms of a shipping fork 68 which is fulcrumed at 69 on the casing, said fork being provided with a lever arm or extension 80 70 to which is connected one end of a link 71 the opposite end of which is connected to one arm of a clutch lever 72 fulcrumed intermediate its ends at 73 on a bracket hanger 90 extending downward from the top of the casing as clearly shown in Fig. 2. At the side opposite the lever 72 there is arranged another lever 74 which is connected by a link 75 with a record throw-off lever 76 95 which is fulcrumed intermediate its ends at 77 on the top of the casing, the upper end of said lever being adapted to strike against the adjacent end of the record and move said record out of engagement with the 100 driving cone 56. The levers 72 and 74 are connected by a rod 78 whereby both of said levers are simultaneously operated. The rod 78 is shifted by means of a cam lever 79 which is fulcrumed intermediate its ends by 105 means of a pivot or bolt 80 connected with a bracket arm extending down from the top of the casing. One end of said cam lever carries a roller 81 which works against a lateral cam face 82 on the cam 28 above referred to, said cam being provided with a peripheral cam face 32 and a lateral cam face 82. The lever 79 is acted upon by the cam face 82, which operates to shift the connecting rod lengthwise and thereby simultaneously rock the levers 72 and 74, one of said levers as previously stated, controlling the tension cone or clutch 57 while the other lever controls the device by which the record is moved out of engagement with 110 the driving cone 56.

The levers 72 and 74 are mounted on rock shafts 73 and 83 and said shafts are provided with short crank arms 84 and 85 which connect with a three-sided lifting 125 frame comprising the two-sided bars 86 and the top horizontally connecting bar 87 which forms a guide rail upon which the free end of the reproducer bar 43 travels, said arm being grooved or notched as shown at 88 to 130

fit said rail as shown in Fig. 1 when the reproducer is in operative contact with the underlying record. 89 designates a retracting spring which operates to hold the roller 5 81 in engagement with the lateral face 82 of the cam, said spring having one end connected to the cam lever 79 and the opposite end connected to the post 37.

After winding up the spring 14 and setting the mechanism in motion, the power of said spring is utilized to drive the main gear 26 and thereby impart motion to the cam 28 which in turn operates the bar 34 and pawl 38 to impart intermittent rotary movement to the sprocket chains 9 which carry the records. When a record reaches the reproducing position, the power of the spring 14 is shifted to the mechanism for clutching the record which is then engaged by the cone 20 above referred to and elevated slightly off the holders after which it is taken up and driven by the cone 56 to which motion is imparted by the main spring 14. The power of the spring is also utilized to drive the feed 25 and return screws 47 and 48 with the effect that the reproducer 42 is moved back and forth across the periphery of the cylindrical record in a manner similar to phonographs now in common use. Thus the entire mechanism of the machine hereinabove described 30 is automatic, requiring no attention on the part of the operator after primarily winding the spring 14, the machine operating to

successively move the records into reproducing position and after causing the reproducer to traverse the surface of the record, to move said records again successively away from the reproducing position. The machine may be constructed in various sizes capable of holding any desired number of 40 records which may be reproduced successively in the manner hereinabove set forth.

I claim:

A phonographic machine comprising a casing, a reproducer, means for propelling 45 said reproducer along the surface of the record, an endless series of records, means for imparting intermittent movement to said series of records operating to successively arrest the movement of the records in reproducing position, a reproducer feed screw, a return screw, and a lever forming an extension of the reproducer arm, and being fulcrumed between the reproducer and said screws, said lever extending to one side of 50 the feed screw and to the opposite side of the return screw and being provided with nut segments respectively adapted to engage said screw one at a time.

In testimony whereof I affix my signature 55 in presence of two witnesses.

HARRY A. SMITH.
